UNITED STATES PATENT OFFICE.

GUILLERMO CALLAHAN, OF SAN GABRIEL, CALIFORNIA.

FOLDING CHAIR.

No. 902,938.

Specification of Letters Patent.

Patented Nov. 3, 1908.

Application filed April 2, 1906. Serial No. 309,501.

To all whom it may concern:

Be it known that I, GUILLERMO CALLAHAN, of San Gabriel, in the county of Los Angeles, in the State of California, have invented a new or Improved Folding Chair, of which the following is a full, clear, and exact description or specification, reference being had to the annexed drawings, and to the letters and figures marked thereon.

10 My said invention which relates to certain new and useful improvements in folding chairs, has for its object, to render such chairs much stiffer in their jointed parts than hitherto, and this object is effected by 15 means of the movable and rigidly adjustable joints wherewith the seat is connected to the back legs and back of the chair, and the front legs are connected to the front part of the seat thereof; the connections or joints of the 20 legs both at the back of the seat, being such that the seat can be folded up against the back part of the chair, and the front legs against the underpart of the seat of the chair, as hereinafter more fully described.

25 Upon the annexed drawings, Figure 1, is a side elevation of a chair constructed according to my present invention when in the unfolded condition or ready for being sat in, or upon. Fig. 2, is another side elevation of 30 the same chair when in the folded condition, and ready for being easily carried about. Fig. 3, is a front elevation of the said chair; Fig. 4, an elevation looking at the rear thereof; and Fig. 5, a plan of my improved folding 35 chair, shown as provided with a seat of plaited cane strips. Fig. 6, is a front elevation; Fig. 7, an elevation at the main face corresponding to Fig. 6; and Fig. 8, a plan on an enlarged scale of the joint of the left front 40 leg, by which said front leg is connected to the under part of the front of the seat. Fig. 9, is an edge or front elevation, on a corresponding enlarged scale, of the joint by 45 which the left rear end of the seat is connected to the left rear leg or back of the chair, this joint being shown with its parts in the position they occupy, when the chair is in the folded condition corresponding to Fig. 2. Fig. 10, is a side elevation corresponding to 50 Fig. 9, that is to say, with its parts in the position corresponding to the chair when folded as shown at Fig. 2. Fig. 11, is another side elevation of the joint shown at Figs. 9 and 10, but with the parts in the 55 folded down position or corresponding with the condition of the chair as shown at Figs. 1,

3 and 4. Fig. 12, is a front elevation corresponding to Fig. 11, and Fig. 13, is a plan corresponding to Fig. 11.

In Figs. 1 to 5, the bars forming the back legs and back of the chair are marked A, the front legs B, and the seat C. The bars A, are connected transversely by the cross members D, D', D'', D''', and the front legs B, are connected transversely by the cross members E, E', E''. The seat C, is connected hingewise to the back bars and legs A, by the upper part F, of the joints, whose lower part is marked G. The upper and lower parts F, and G, of each rear joint, are attached to the under part of the seat C, by screws inserted through holes a, b, and c, shown in the upper part F, and by screws d, to the rear legs as shown at Figs. 1, 2, 10 and 11. The upper and lower parts F, and G, of each rear joint are not only connected by the pivot e, Figs. 1, 2, 10 and 11, but these parts are also connected by a bar H, Figs. 2, 9, 10, 11 and 12, whose upper end is connected pivotally by the pin f, to the upper part F, of each rear joint, and whose lower end is connected to the lower part G, of each rear joint, by the pinching bolt g, passing through a hole therein and through the quadrantal slot I, in the part G, of each of the rear joints. The bolt g, being provided with a nut h, for tightening the parts, while to still more securely bind the parts together, when the chair is in the opened condition, a thumb-screw J, passing through the bar H, is 90 screwed into the tapped boss K, Figs. 1, 2, 9, 10, 11 and 12.

With respect to the front legs B, these are connected to the front under part of the seat C, by the joints shown at Figs. 1, 2, 3, 6, 7 95 and 8. The front legs B, are each driven tight into the sockets L. Each socket L, is connected by the pivot pin i, to the upper part M, of the front joints, and is provided with a pinching nut k, screwed on a pin or 100 stud projecting from each socket L, through a quadrantal slot N, in the wing of the part M, of each front leg joint. By tightening or loosening the nuts k, the front legs B, are capable of being fastened in either the open 105 position shown at Figs. 1, 3 and 4, or in the folded position shown at Fig. 2. The extreme folded position of the front legs B, is shown by dotted lines in Fig. 2.

It is here explained that as a chair has 110 right and left ends, the joints for connecting the legs with the right and left ends of the

back, seat, and front legs are necessarily made "right" and "left", and that for the joints which are to be used for the right end of a chair, the parts constituting the right end joints, are in reverse position to corresponding parts in the left end joints, as more particularly shown at Figs. 3 and 4 of the annexed drawings.

Having now described the nature of my 10 said invention, and the best system, mode or manner, I am at present acquainted with, for carrying the same into practical effect, I desire to observe in conclusion that what I consider to be novel and original and therefore 15 claim as the invention to be secured to me by Letters Patent, is as follows:

In a folding chair, a seat hingedly connected to the back and rear legs, a member connected to the rear legs and provided with a 20 quadrantal slot, a bar pivotally connected to

the seat at one end, a bolt and nut on the other end of the bar engaging the said slot for locking the seat in position, said member having a tapped hole, a thumb screw on the said bar adapted to engage with the said 25 tapped hole when the seat is in horizontal position, front legs hinged to the seat, a quadrantal vertical wing secured to the seat and provided with a quadrantal slot, a pinching stud and nut projecting from the 30 said leg and engaging the last named slot for locking the front legs in position.

In testimony whereof I have hereunto set my hand and seal in the presence of two subscribing witnesses.

GUILLERMO CALLAHAN. [L. s.]
